CLAIM

The ornamental design for a control electrode for an X-ray tube cathode as shown and described.

DESCRIPTION

FIG. 1 is a top-front perspective view of a control electrode for an X-ray tube cathode according to the claimed design.

FIG. 2 is a top-rear perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a top-front perspective view of the control electrode for an X-ray tube cathode of FIG. 1 within a cathode assembly shown in environment.

FIG. 10 is a sectional view of control electrode for an X-ray tube cathode of FIG. 1 along line 10-10 in FIG. 3.

FIG. 11 is a sectional view of the control electrode for an X-ray tube cathode of FIG. 1 along line 11-11 in FIG. 3; and,

FIG. 12 is a sectional view of the control electrode for an X-ray tube cathode of FIG. 1 along line 12-12 in FIG. 3.

The dash-dash broken lines in the drawings illustrate portions of the control electrode for an X-ray tube cathode that form no part of the claimed design.

The oblique broken line shading illustrates interior portions of the control electrode for an X-ray tube cathode that form no part of the claimed design.
